Frank Wachman, New York, N. Y.

Application June 30, 1939, Serial No. 282,180

3 Claims. (Cl. 312—138)

This invention relates generally to cabinets and has particular reference to cabinets for storing articles for sale and displaying specimens of them.

One object of the invention is to provide a cabinet of the kind mentioned which is simple in construction, easy to assemble and dis-assemble and which is sturdy and durable in construction.

Another object is to provide an enclosing casing for a rotatable storage and display device which is substantially dust-proof and which is so constructed as to afford a maximum of glass in the display part of the casing. This is accomplished by making the display portion exclusively of glass doors or windows having light sash frames; that is, there are no parts such as posts or jambs between the windows or doors.

Another object is to provide a construction in which a rotary storage and display member is supported upon bearings which will hold the storage and display member accurately in a vertical position and permit the rotation of the member when desired. This support is important in applicant's particular construction because the rotary member is used to support and hold casing parts in vertical position and that cannot be done accurately unless the vertical position of the rotary member is maintained. This is due to the fact that, as before stated, there are no jambs or posts between the exterior doors to stiffen the casing.

With the foregoing and other, as well as incidental, objects in view, the invention consists in a novel construction and relative arrangement of parts, embodiments of which are shown in the accompanying drawings and the novel features of which are pointed out in the claims appended hereto.

In the drawings:

Figure 1 is a top view of one of the cabinets of this invention.

Fig. 2 is a section on the line 2—2 of Fig. 1.

Fig. 3 is a section on the line 3—3 of Fig. 2.

Fig. 4 illustrates details of the construction of the door or window feature.

Fig. 5 is a view along the line 5—5 of Fig. 3 illustrating some of the features also shown in Fig. 4.

Fig. 6 is a section of a modification of the apparatus illustrated in Figs. 1 to 3 inclusive.

Fig. 7 is a detail of a roller bearing support for the storage and display member of the cabinet of Fig. 6.

Fig. 8 is a section on the line 8—8 of Fig. 6.

The cabinet shown in Fig. 2 comprises a rotary member 10, rotatably supported by bolts 11 and 12 through a top piece 13 of the cabinet and a bottom piece 14. These bolts are employed so as to leave more of the rotary member free for use in storing stock than would be possible if an axially extending shaft was employed. A long shaft or something of that kind would interfere with putting stock in the compartments herein-after described. The rotary member has a top plate 15 and a bottom plate 16, and between these plates are walls 17, 18, extending vertically between the plates 15 and 16 and meeting at right angles as at 21. In the preferred construction these walls are so arranged that there are intersecting spaces 19 and 20, each extending the full diameter of the rotary member and thereby leaving the center of that member where the spaces 19 cross, so that any shelving can be used. Some shelves may extend the full length of the spaces 19; that is, substantially the full diameter of the rotary member, or shelves may extend only to one of the corners 21 and leave the rest of the space on that plane free from shelving. In fact by using the angular construction afforded by the walls 17 and 18 it is possible to have a wide variance in the arrangement of the shelving according to number or according to the kind of article which is to be stored.

30 The openings 20 may be closed by doors 22 and the outer faces of these doors may be provided with clips for holding articles for display or the doors may carry small display shelves or racks for different articles.

35 The outer part of the angle formed by the walls 17 and 18 may also be provided with display shelves or with wire loops such as shown in 23 for displaying articles such as neck ties or similar things.

40 The top plate 13 also forms the bottom for a storage compartment 24 consisting of sides 25 and a pair of covering members 26 hinged as at 27. Brackets 28 of a well-known type may be employed for holding the cover members in raised position.

45 Instead of compartment 24 being used as a storage compartment it may be employed to accommodate a sale announcing phonograph or a motor where a drive for the rotary member 10 is to be employed.

The base of the cabinet is preferably composed of two sections, the one shown at 31 being normally of a material which will not be injured or marred by mops and brooms, while the section 32 may be of any decorative material to

conform with the rest of the cabinet or with the store fixtures.

In some constructions the top plate 13 may be constructed to form upwardly extending ledges 33 which, in combination with downwardly turned ledges 34 on the sides 25, will afford supports for inserting advertising cards and the like.

Integral with the bottom plate 14 and the bottom side wall 32 is a series of members 36 extending around the cabinet and affording supporting sills for the display windows or doors.

As above stated, the display portion of the casing is composed entirely of doors or windows in order to increase the visibility of articles on display. In addition, the doors or windows serve to support the top plate 13 to prevent it from tilting and they further serve to stiffen and hold the entire upper part of the cabinet in position.

The display section of the cabinet is composed of what is for convenience usually referred to herein as the control door or window 37 (the latter term is usually hereinafter employed) and a series of display windows 38. In the embodiments shown herein there are seven (7) of these display windows, the display part of the cabinet being octagonal.

The control window and the display windows are hinged in the top plate 13 and the bottom sill 36 and their adjoining edges are shaped to form miter joints when the windows are closed to bring the abutting edges together. The hinge construction employed comprises members 41 set in the upper and lower ends of the frames of each of the windows and fastened in position as by the screws 42 (Fig. 3) only one of which is shown in Fig. 5. For a reason which will be clear later, the hinge members 41 are constructed to extend slightly beyond the vertical edges of the frames to which they are attached, and carry studs or pins 43 engaging sockets in the top plate 13 and the sill members 36. In assembling, the lower pins or studs 43 are inserted in holes provided for that purpose and a like operation is performed when putting the top part 25 of the cabinet in place.

From the immediately foregoing it will be seen that the frames of the display windows or doors serve to space the top plate 13 from the bottom sill 36, thereby insuring correct alignment or relation between all of the parts and the base of the device.

Each of the windows is, of course, provided with a pane 44 of glass held in position in the frame by any suitable means.

The control door 37 is provided with a lock 45, the bolt of which cooperates with the adjacent edge of one of the display windows 38. If all of the display doors or windows are closed, in which positions they are shown in the drawings, and the control door 37 is closed and locked, unauthorized access to the interior of the cabinet is prevented. This is effected by a tongue and groove construction at the abutting faces of the windows which also serves to make dust-proof seals.

It is preferred to have the grooves referred to cut in the hinged sides of the windows and the tongues on the free edges of the adjacent windows. These tongues and grooves are designated respectively 46 and 47 in the drawing. The tongues are, as shown, inclined inwardly with respect to the face on which they are formed. Owing to the location of the pivot pins 43 with respect to the vertical edge of the frame to which

the members 41 are attached and the cross-sectional shape of the tongue, closing of the hinge carrying member will apply pressure on the outside face of the tongue 46 and give a final closing movement to the tongue carrying window. In addition, the tongue will be engaged by the outer wall of the groove and the tongue member locked against opening when the preceding window is closed. By this arrangement, if the display window 38 at the left of the control door 37 is closed and then the next window and so on around to the control door are closed in sequence, all of the display doors or windows will be locked. The control door has a grooved edge cooperating with a tongue on the edge of the display door next to the right so that when the control door is closed and locked the entire set of doors or windows will be locked. The tongue is omitted at the free edge of the control door 37 and there is no groove in the edge of the display window adjacent the free edge of the control window. If it is desired to open the display windows for any purpose such as cleaning, or stock replacement, the control door may be unlocked and opened after which the display windows can be opened one after the other in regular sequence extending all around the cabinet.

The form of cabinet illustrated in Figs. 6, 7 and 8 is for use on a counter. It comprises a bottom plate or board 51 which carries a pivot stud 52 upon which a display cabinet resembling the floor cabinet in most respects may be mounted to rotate as a unit. Between the board or plate 51 and the bottom member 53 of the cabinet is a bearing support which serves to hold the display cabinet in proper relation to the base 54. This bearing comprises a pair of members 54 which are formed to surround the bearing stud 52 and fastened together along their contacting faces. Each of the members 54 is continued or extended to provide rods 55 extending radially from the stud 52. Mounted upon each of the rods 55 is a roller 56 held in position on the rod by a head 57 on the end of the rod. The rollers may be of any desired material, but are preferably rubber covered metal tubes. Instead of using a single tube on each rod a series of short tubes may be used on each rod, thereby lessening to some extent frictional resistance when the display cabinet is turned on the base 51. The bearing construction of Fig. 7 may, if desired, be, and in fact preferably is, used in the floor cabinets such as illustrated in Figs. 1 to 5 inclusive, although this will, of course, involve some relative re-arrangement of parts to give room for the bearings.

The counter cabinet of Fig. 6 has the same construction of the exterior or vertical face; that is, it is composed solely of a control door 61 and display doors 62 interlocking as previously mentioned in connection with the floor cabinet. The rotary member has crossing compartments 63 and 64 which may be provided with any desired kind of shelving and the outer faces closed by hinged doors 65. In the counter cabinet, as well as the floor cabinet, the construction is such that the periphery of the storage and display section is enclosed largely by glass, this being due to the fact that no pillars or jambs are used.

The cabinets shown and described provide what might be termed a compact retail unit in which, for example, men's shirts, hose, ties and similar articles may be stored in the rotary section and specimens displayed on the doors 22 and 65 and on the hangers 23, as well as small shelves in

vertical alignment with the hangers. Normally only the control door 37 will be used in making sales and the rotary member will be turned to bring opposite that door the specimen which the customer wishes to examine and the stock of those articles will usually be stored in the interior of the display section adjacent to the displayed specimen. In cleaning the glass or for convenience or stocking up the interior the control door 37 may be swung open and then all of the other doors opened in sequence around the cabinet in the manner previously described.

While the invention has been illustrated and described in considerable detail, that has been done merely to explain the invention and it is not desired to be limited to any extent except as indicated in the claims which follow.

What is claimed is:

1. A display cabinet comprising a plurality of display windows having their vertical edges constructed to abut as miter joints when the windows are closed, and a tongue and groove seal between each cooperating pair of said vertical edges, the groove in each instance acting against the associated tongue to effect a final closing movement of the tongue-bearing window, and hinges for the windows constructed to swing the windows about axes outside the vertical sides of the windows.

2. A display cabinet casing comprising top and bottom members, and a peripheral casing composed solely of a plurality of frames each supporting a pane of glass, said frames being pivoted adjacent vertical edges thereof between the top and bottom members and their cooperating vertical edges being constructed to interlock when closed in a certain order, and a control window hinged like the others and interlocking at its

hinged side with the frame of the next adjacent window, and a lock on the free edge of the control window cooperating with the hinged side of the next adjacent window frame to lock the control window and closed display windows.

3. In a display cabinet, a casing composed of a plurality of display windows each consisting of glass mounted in a frame, a cabinet top piece and a cabinet bottom piece, hinge members attached to the upper and lower edges of each display window frame and extending beyond the vertical edge of said frame, studs on said members pivotally engaging recesses in the cabinet top and bottom pieces, the pivoted movement being on an axis outside of but parallel to the vertical edge of the display window frame, a groove in one vertical edge of each except one of the display window frames and a tongue on each of the display window frame edges one of which cooperates with each of said grooves, all of said tongues and grooves being in engagement and sealing the abutting edges of the display window frames together when the display windows are closed, and a hinged control window having a groove in its vertical edge at its hinged side cooperating with the tongue on the next adjacent display window frame and a lock on its free edge cooperating with the above excepted display window frame, the adjacent edges of said excepted display window frame and the control window being tongueless and ungrooved, the construction being such that opening said control window will disengage its groove from the tongue on the next frame and thereby free the other windows for opening by disengaging the tongues and grooves one after another in a fixed sequence.

FRANK WACHMAN.
